Primary Examiner — Cynthia Ramirez*Assistant Examiner* — Xavier Marti-Santos(74) *Attorney, Agent, or Firm* — Maier & Maier, PLLC(57) **CLAIM**

The ornamental design for a mirror with illumination, as shown and described.

DESCRIPTION

FIG. 1 is a front view of a mirror with illumination, showing my design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The broken lines in the Figures are for the purpose of illustrating portions of the mirror with illumination and form no part of the claimed design.
